[57] CLAIM

The ornamental design for a housing with straps for a

shoulder coil for a magnetic resonance imaging device, as shown and described.

DESCRIPTION

FIG. 1 is a front, top and left side perspective view of a housing with straps for a shoulder coil for a magnetic resonance imaging device showing my new design. The broken line showing is for illustrative purposes only and forms no part of the claimed design;

FIG. 2 is a left side elevational view thereof. The broken line showing is for illustrative purposes only and forms no part of the claimed design;

FIG. 3 is a top plan view thereof;

FIG. 4 is a front elevational view thereof. The broken line showing is for illustrative purposes only and forms no part of the claimed design;

FIG. 5 is a rear elevational view thereof. The broken line showing is for illustrative purposes only and forms no part of the claimed design;

FIG. 6 is a bottom plan view thereof;

FIG. 7 is a right side elevational view thereof. The broken line showing is for illustrative purposes only and forms no part of the claimed design; and,

FIG. 8 is a front, top and left side perspective view thereof. The broken line showing is for illustrative purposes only and forms no part of the claimed design.

FIG. 1
